BINARY STORAGE CIRCUIT ARRANGEMENT

This invention relates to a binary storage circuit arrangement comprising a group of trigger circuits each having a first and a second transistor whose base electrodes are connected to the collectors of the other transistors so that the trigger circuits may be in two different information states in which one of the transistors is conducting and the other is cut off or conversely.

Particularly if such a storage circuit is constructed in the form of an integrated circuit, the heat dissipation should be as low as possible.

A storage circuit of this kind is already known and it comprises means for varying the supply voltages of the transistors so that the trigger circuits may be in a steady state of low dissipation or in an operational state of high dissipation. In this case the supply voltages of the collectors of all triggers circuits are simultaneously changed so that the triggers are simultaneously in the state of low or high dissipation. In the known arrangement the triggers are provided with individual write and read conductors, which is particularly undesirable in integrated circuits.

The invention provides an efficient solution in which one of the triggers of a group is selected and is brought into a state of higher dissipation, said trigger coupling itself with control-conductors common to the group and, as the case may be, with one or two common read conductors owing to the resultant voltage variations. A non-selected trigger is not charged so that the tolerances are favorable and the supply current and supply voltage and hence also the dissipation may be very low, while the stability is maintained. In spite thereof the switching rate is high.

The invention is characterized in that the collectors of the first and second transistors of each trigger are connected to the collectors of a third and fourth respectively and the base electrodes of the third and fourth transistors are connected to a first write conductor and a second write conductor respectively common to the group of triggers and the emitters of said four transistors of each trigger are connected to each other and to an identifying point individually associated with the trigger concerned, the potential of said point normally having such a steady value that the trigger is in a steady state of low dissipation, in which the first or the second transistor is slightly conducting and the other transistors are cut off, there being provided means for varying the potential of the identifying point of one of the triggers of the group so that the trigger is in a state of higher dissipation and a write pulse across the first or the second write conductor renders the third or the fourth transistor of the trigger conducting for driving the trigger into a given, desired information state.

The invention will be described more fully with reference to one embodiment shown schematically in the drawing.

The FIGURE shows one trigger circuit of a group of identically designed trigger circuits and a number of common components. The FIGURE shows furthermore in broken lines a few variants.

Essentially the trigger comprises the transistors T_1 and T_2 . The collectors thereof are connected through resistors R_1 and R_2 to a supply point $+V$, the voltage of which may be equal to $+1$ V to ground. The collectors are furthermore connected crosswise to the base electrode of the other transistor.

In the embodiment shown the transistors are each equipped with two emitters e_{11} , e_{12} and e_{21} , e_{22} respectively. The emitters e_{12} and e_{22} are connected to ground. The emitters e_{11} and e_{21} are connected to an individual identifying point P of the trigger and are furthermore connected to the emitters of the transistors T_3 and T_4 , which perform a gate function, as will be apparent below. The collectors of the transistors T_3 and T_4 are connected to the collectors of the transistors T_1 and T_2 and the base electrode of T_3 and T_4 are connected to the write conductors S_1 and S_2 , common to the whole group of triggers.

The collectors of the transistors are connected at the points A and B to the emitters of the multi-emitter transistors T_5 and T_6 , which serve as read gates and perform an or-function, as will be apparent hereinafter. The other emitters of the

transistors T_5 and T_6 are connected in a corresponding manner to the points A and B of other triggers of the group. The base electrodes are grounded and the collectors are connected to read conductors L_1 and L_2 , which are common to the whole group.

The various triggers of the group are controlled by means of a selection circuit comprising the transistors T_a , T_b , T_c , and so on, which are arranged in known manner in rows and columns of a matrix. The base electrodes of the transistors of one row are connected to one and the same control-conductor X_1 or X_2 respectively, whereas the emitters of the transistors of the same column are likewise connected to one and the same control-conductor Y_1 or Y_2 respectively. The collectors of the transistors are connected to the individual identifying points of the various triggers of the group.

In the rest position of the arrangement one of the transistors T_1 or T_2 of each trigger is always slightly conducting, whereas all further transistors are cut off. If, for example, the transistor T_1 of the trigger shown is conducting, a comparatively weak current of, for example, 1 mA flows from the supply point $+V$ via resistor R_1 and emitter e_{12} of transistor T_1 to ground. The dissipation in the trigger is then of the order of 1mW and hence very low. The emitter e_{11} of transistor T_1 is then idle because the transistor T_a is cut off. More particularly, the voltage at point B is then equal to $+V_j$ and the voltage at point A equal to $+V_k$, wherein V_j and V_k are the "junction" voltages between the base and the emitter or between the collector and the emitter respectively of an over-excited transistor. With silicon transistors these voltages V_j and V_k may be equal to about 0.7 V and lie between 0 and 0.4 V respectively. Consequently the voltage at point B is higher than that at point A , the latter being lower than the junction voltage V_j so that transistor T_2 is cut off. Since the voltages at points A and B are higher than ground potential, the transistors T_5 and T_6 are cut off. Also the transistors T_3 and T_4 are cut off because no current passes through transistor T_a .

If information has to be read from the trigger circuit or new information has to be written, the trigger is individually indicated by means of the selection circuit. To this end a positive pulse is applied via known means (not shown) to the control-conductor X_1 , and the conductor Y_1 is, in addition, connected to an appropriate supply source, particularly a current source, as a result of which the transistor T_a becomes conducting and a higher current starts to flow across the resistor R_1 , the collector and the emitter e_{11} of the transistor T_1 , the identifying point P and the transistor T_a . Thus the voltage at point P drops below ground potential so that the emitter e_{12} becomes idle. Owing to the high voltage drop across resistor R_1 the voltage at point A drops below ground potential to an extent such that the transistor T_5 becomes conducting via its emitter connected to point A and a read signal characteristic of the information state of the selected trigger appears across the read conductor L_1 , connected to the collector. It should be noted that if the transistor T_2 instead of transistor T_1 had been conducting a read signal would be applied in the same manner to the read conductor L_2 .

When transistor T_5 is conducting, as supposed above, the voltage at point A is equal to $-V_j$, i.e., the junction voltage between emitter and base) and is thus held at a fixed value. The voltage at point P is then equal to $-V_j - V_k$ i.e., the voltage $-V_j$ of point A minus the voltage V_k between collector and emitter of transistor T_1). The voltage at point B is then equal to $-V_k$, i.e., equal to the voltage $-V_j$ minus V_k of point P plus the junction voltage V_j . The voltage at point B is lower than ground potential, it is true, but the transistor T_6 remains cut off because the voltage V_k is lower than the junction voltage V_j .

The transistor T_2 also remains cut off because the voltage difference between the base and the emitter e_{21} is equal to the voltage difference between points A and P and hence equal to V_k , i.e. lower than the junction voltage V_j .

The transistors T_3 and T_4 are cut off because the voltage of the write conductors S_1 and S_2 is normally low, for example, equal to $-2V$.

If new information has to be written in the selected trigger, the voltage of the write conductor S_1 or S_2 is increased according as the transistor T_1 or the transistor T_2 has to be conducting, for example, to ground potential. It is supposed that a positive pulse is applied to the conductor S_2 ; transistor T_4 then becomes conducting so that the voltage at point B drops and transistor T_1 is cut off. The voltage at point A thus rises over that at point B so that after cutting off of the transistor T_4 at the end of the pulse finally transistor T_2 instead of T_1 is conducting.

If on the contrary a positive write pulse is applied to the write conductor S_1 , transistor T_3 becomes conducting, but finally transistor T_1 remains nevertheless conducting. New information can thus be written on the former without the need for further means.

It should be noted that a positive write pulse at the write conductors S_1 or S_2 does not affect non-selected triggers, because no current can flow across the identifying points P so that the transistors T_3 and T_4 remain cut off.

In a variant of the arrangement the emitters e_{12} and e_{22} of the transistors T_1 and T_2 are lacking and the identifying point P is grounded via the resistor R_3 , shown in broken lines. The sole difference in operation from the first arrangement resides in that in the rest position the current through the conducting transistor flows to ground via the emitter e_{11} or e_{21} and the resistor R_3 instead of flowing through the emitter e_{12} or e_{22} . Write pulses of the conductors S_1 or S_2 cannot affect non-selected triggers because the voltages of the base electrodes of the transistors T_3 and T_4 cannot exceed those of the emitters. The use of resistors in integrated circuits has some disadvantages so that the arrangement first described, comprising two emitters in each transistor, is to be preferred.

In principle it is not necessary to use two read conductors, a single one will suffice. The appearance or non-appearance of an output signal at a read conductor is in itself an indication of the information state of a selected trigger circuit. For example, the transistor T_6 and the read conductor L_2 may be omitted. In order to hold also in this case the voltage at point B of a selected trigger at a given value, when transistor T_2 is conducting, it is desirable to connect the points B to ground each via a diode. This diode then performs the same function as the emitter-base junction of transistor T_6 .

Alternatively it is possible to combine pairwise the read and write conductors, for example, the conductors L_1 and S_1 , and the conductors L_2 and S_2 .

In a first variant this may be achieved by omitting the conductor S_2 and by coupling the conductor L_2 with the base of transistor T_4 via a diode D as is indicated in broken lines. In reading this diode has no effect, because it remains cut off. However, if the voltage of the conductor L_2 is raised for writing information, the diode becomes conducting when the Zener voltage is exceeded and the voltage at the base of transistor T_4 is increased so that the transistor becomes conducting.

It is advantageous to construct the diode as a second emitter of the transistors T_3 and T_4 as is indicated in broken lines at the transistor T_3 , which is provided with a second emitter e_{24} . The conductor S_1 may then be dispensed with. When a positive pulse appears at conductor L_1 and when the Zener voltage is exceeded, the voltage of the base of transistor T_3 will increase.

The use of only two conductors, which can serve both in reading and writing, is particularly important in integrated circuits.

What is claimed is:

1. A binary storage element for a group of trigger circuits, each element comprising a first transistor having a base, a collector, and an emitter, a second transistor having a base, a collector, and an emitter, means for cross coupling the bases and collectors of the first and second transistors, whereby the first and second transistors comprise a trigger circuit wherein one

of the transistors is conducting and the other is cut off, a third transistor having a base, a collector and an emitter, a fourth transistor having a base, a collector, and an emitter, means for connecting the collector of the first transistor to the collector of the third transistor, means for connecting the collector of the second transistor to the collector of the fourth transistor, means for connecting the base of the third transistor to a first write conductor, means for connecting the base of the fourth transistor to a second write conductor, means for connecting

- 5 the first and second write conductors to the bases of corresponding third and fourth transistors of other circuit elements in the group of trigger circuits, means for connecting emitters of the four transistors in each element to a common identifying point, the identifying point comprising means for 10 selectively providing a first and a second potential, the first potential having a value sufficient to maintain the trigger in a rest position of low power dissipation wherein alteration of the conductive state of the trigger is prevented, the second potential having a value sufficient to enable the trigger to switch 15 conductive states of the first and second transistors in response to a signal on the first or second write conductor, means for controlling the potential of the first and second potential providing means, the first and second transistors each having a further emitter, and means for connecting the 20 further emitters of the first and second transistors to a common point of constant potential.

2. A storage arrangement as claimed in claim 1 wherein the collector of at least the first transistor of the trigger is connected to a read gate constructed as an or-gate with a plurality 25 of control-inputs connected each to the collectors of the first and third transistors of different trigger circuits, the output of the gate being connected to a read conductor common to the group of triggers so that, if the first transistor is highly conducting the threshold of the gate input concerned is exceeded and a read signal is applied to the read conductor.

3. A storage arrangement as claimed in claim 2 wherein the or-gate is constructed as a multi-emitter transistor, the various emitters of which form the control-inputs, the collector being connected to a read conductor and the base being connected to a point of constant potential.

4. A storage arrangement as claimed in claim 3 wherein also the collectors of the second and fourth transistors of a number of trigger circuits are connected to different emitters of a multi-emitter transistor, the collector of which is connected to 40 a second common read conductor and the base of which is connected to the point of constant potential.

5. A storage arrangement as claimed in claim 3 wherein the collectors of the second and fourth transistors of the trigger circuits are connected via a diode to the point of constant potential.

6. A storage arrangement as claimed in claim 2 wherein the read and write conductors are pairwise combined and the base electrodes of the third and fourth transistors are connected via at least one diode to the read and write conductor concerned.

7. A storage arrangement as claimed in claim 6 wherein the diodes are constructed in the form of second emitters of the third and fourth transistors.

8. A storage arrangement as claimed in claim 1 wherein a number of switching transistors are arranged in the rows and columns of a matrix, while the bases of the transistors of one and the same row are connected to the same row control-conductor and the emitters of transistors of one and the same column are connected to the same column control-conductor, and the collectors of the transistors are connected to the individual identifying points of the various trigger circuits, there being provided means for applying a current or voltage pulse to one column control-conductor and one row control-conductor so that the switching transistor concerned becomes conductive and the trigger circuit connected to the collector thereof gets into the state of high dissipation.
